STOVE CONSTRUCTION

Claude M. Dibble, Joliet, Ill., assignor to Moore
Brothers Company, Joliet, Ill., a corporation of
Illinois

Application October 16, 1929, Serial No. 400,135

11 Claims. (Cl. 126—39)

This invention relates in general to stove construction, and has more particular reference to improvements in the burner portion of gas ranges.

A principal object of this invention is to provide the burner portion of a gas range with means for concealing the valves, the manifold, and the manifold supply pipe.

An important object of the invention is to provide the burner portion of a gas range with means for protecting the valves, the manifold, and the manifold supply pipe from the heat of the burners.

Another important object of the invention is to provide a simple means for concealing the manifold of the burner portion and to mount such a means so that it is readily and easily removable in order to adjust and to clean the valves and the mixing chambers.

Numerous other objects and advantages of the invention will be apparent as it is better understood from the following description, which, when taken in connection with the accompanying drawings, discloses a preferred embodiment thereof.

Referring to the drawings,

Figure 1 shows a perspective view of a gas range embodying the principles of the invention;

Fig. 2 is an enlarged plan view of a portion of the stove shown in Fig. 1, having parts removed to show certain construction details;

Fig. 3 is a partial elevation of the parts shown in Fig. 2, showing parts in section and parts cut away;

Fig. 4 is a fragmentary section taken substantially on the line 4—4 of Fig. 3;

Fig. 5 is a fragmentary section taken substantially on the line 5—5 of Fig. 2;

Fig. 6 is a section taken on the line 6—6 of Fig. 3;

Fig. 7 is a perspective view of a part of the stove shown in Fig. 1;

Fig. 8 is a partial perspective view of a frame supporting member of the stove of Fig. 1;

Fig. 9 is a partial perspective view of a frame member of the stove in Fig. 1; and

Fig. 10 is a section showing an assembled relation of the parts shown in Figs. 7, 8 and 9.

For the purpose of illustrating the invention, the drawings show a gas stove or range supported on legs 11 and having a substantially rectangular base frame 12, shown in Fig. 1, supported on the legs 11. A combined broiler and oven portion 13 of usual construction is supported on the base frame 12 at an end of the range, providing as usual number of ovens 14 which are closed by suitable doors 15.

An open burner portion generally designated

by the reference character 16 is supported on the base frame 12 adjacent the ovens 14 and extends to the end opposite the ovens. The burner portion 16 has a corner frame member 17 which is secured at its lower end to the base frame 12 by means of a bolt 18 and which projects vertically therefrom. The corner frame member 17 is substantially angle shaped, having a front leg 19 which is provided with a slot 21 intermediate its ends. The top end of the corner frame member 17 flares outwardly to provide an enlarged portion 22, as shown in Fig. 3. A corner frame member 23 co-operates with the corner frame member 17 to support the top of the burner portion 16 and is suitably secured to a side 24 of the broiler and oven portion 13 and has the same sectional shape as the member 17. A front leg 25 of the member 23 is cast to terminate above the lower end of the member 17, providing a recessed or slotted portion 26 at its lower end to correspond with the slot 21 in the member 17.

The front faces 19 and 25 of the corner frame members are cast in the form of an arc which is provided with a ledge 27 arranged along the vertical inner edge of each of the members 17 and 23. The ledges 27 terminate at their lower ends in lugs 28 which are cast on the members 17 and 23 and which are offset behind the ledges 27. The lugs 28 have grooves 29 transversely of their upper ends to provide overhanging projections 31 for each lug and extend downwardly to the upper sides of the slot 21 and the corresponding cut-away portion 26 in the corner frame member 23. Slots 32 are provided in the lugs 28 and extend from the bottom upwardly to a point just below the transverse grooves 29 which provide the overhanging projections 31. The corner frame members 17 and 23 are shown more particularly in Fig. 9.

A frame supporting member 33, having lugs 34 on each end, is cast with an upstanding flange 35 near each end. The supporting member 33 is adapted to be positioned longitudinally of the burner portion 16 between the corner frame members 17 and 23 and to be secured in place above the slot 21 by the lugs 34 on the member 33 engaging with the slots 32 and held therein with washers 36 and nuts 37 threaded on the ends of the lugs 34 against the rear faces of the slotted lugs 28. The upstanding flanges 35, near each end of the member 33, are offset from the top edge 38 of the frame supporting member, as shown in Fig. 8, and are adapted to seat in the grooves 29 below the overhanging projections 31 of the lugs 28. The member 33 is substantial-

ly angle shaped in section, having an internal ledge 39 cast at the bottom of the frame supporting member, and extending between the offset flanges 35. A space is thus provided in the 5 burner portion 16 below the member 33, into which a usual drip pan 41 is arranged to seat in the slot 21 and the corresponding recessed or slotted portion 26 of the member 23. A utility drawer 42 for cooking utensils is arranged below 10 the drip pan 41 and extends between the corner frame member 17 and the side 24 of the oven and broiler portion 13, as shown in Fig. 1.

The burner portion 16 is provided with a substantially rectangular top frame 43 which is 15 arranged over the burner portion 16 and is supported at its front by the corner frame members 17 and 23 and by suitable stove frame members (not shown) at its back. The top frame 43 is cast with depending sides 44 along its front and 20 end and is an open frame having inner edges 45 which are cast to depend from the top frame and to terminate in an inwardly disposed horizontal flange 46 which extends around the open portion of the frame. The flange 46 is provided 25 to support a usual burner grate 47, as shown in Fig. 1. An arcuate horizontal lug 48 is cast at the front side of the open portion and extends inwardly from the flange 46 for the purposes to be hereinafter more fully described. A similar 30 lug 49 is cast at each side of the top frame open portion to adapt the frame for use on burner portions arranged at the right or left side of a gas range.

Positioned below the burner grate 47 are a 35 plurality of burners 51 and 52 having burner lead pipes 53 which are formed at their ends to provide mixing chambers 54 for mixing air of combustion with the gas for the burners. The burners 51 are supported at the back side of 40 the top frame 43 by means of T-brackets 55 which are bolted to projections 56 from the burners and supported on lugs 57 projecting from the top frame 43. A suitable pilot burner 58 is provided substantially centrally of the burners 51 45 and 52 for the purpose of lighting the burners and has a lead pipe 59 which terminates in a pilot valve 61 communicating with a manifold 62 arranged across the front of the burner portion 16. This manifold is suspended from the 50 top frame 43 by means of a bifurcated bracket 63 which has a horizontal portion adapted to conform with the lug 48 to which it is bolted by a countersunk screw 64 and a nut 65. The bracket 63 has furcations 66, which conform with 55 the contour of the manifold 62 and which partially encircle a portion thereof. The bracket 63 serves to hold the manifold in annular grooves of a plurality of lugs 67, which are cast to the under side of the top frame 43 and depend therefrom to engage portions of the manifold.

The manifold 62 extends substantially across the front side of the burner portion 16 and has a cap nut 68 which closes the oven end of the manifold. The other end of the manifold threads 65 into a pipe L 69 which communicates with a manifold supply pipe 71 mounted along the side of the burner portion 16 by means of a bolt 72 passing through the lug 49 and a bracket identical to the suspending bracket 63 and grooved depending lugs 73. The manifold supply pipe is threaded on its end opposite the pipe L 69 for the purpose of connection to a source of fuel supply from which fuel may be supplied through the supply pipe and the manifold to the burners in the burner portion 16 and to the ovens 14, the fuel

flow being controlled by a plurality of valves 74 and 75 suspended from the manifold 62 with which the valves are threadably connected. The valve 75, communicating with the manifold 62, has suitable pipe connections 76 to the oven and broiler portion 13 and is provided to control the amount of fuel supplied to the ovens. The valves 74, communicating with the manifold 62, also communicate with the mixing chambers 54 on the ends of the burner pipe leads 53, and the valves control the fuel supplied to the burners 51 and 52. The valves 61, 74 and 75 have valve stems 77 which extend outside of the burner portion 16 and are provided with suitable control handles 78 which are secured to the stems 77 by means of suitable screws 79.

The mixing chambers 54 are of usual or preferred construction and are provided with adjustable air shutters 81 adapted to have set adjustments and to be held in an adjusted position by means of set screws 82. The air shutters are provided to control the amount of air admitted to the chambers 54 for mixing with the gas for the burners.

A heat baffling means is provided between the 25 burners and the manifold 62 and the valves 61, 74 and 75 for the purpose of protecting the valves and manifold from the heat of the burners and to protect the valves against sticking, due to this heat. The heat baffling means comprises a front 30 baffle plate 83 which is angle shaped and which extends inwardly and depends downwardly from the flange 46 at the front side of the burner portion to below the valves 74 and which has a plurality of slots 84 arranged to co-operate with and 35 to slide around valve portions 85, as shown in Figs. 3 and 4. The slots 84 have a side formed arcuately outwardly of the slots to permit access to the set screws 82 without disturbing the plate 83 for adjusting the mixing chambers 54 to control the amount of air supplied to the burners.

The front baffle plate 83 is suspended from the flange 46 of the top frame 43 by slotting the baffle plate and sliding it between the face of the bracket 63 and the lower face of the lug 48, so that the slot cooperates with the bracket mounting screw 64, as shown in Fig. 5. The baffle plate 83 extends from the oven side 24 longitudinally of the burner portion 16 and is slotted at its end to slide around the pipe L 69 which 50 connects the manifold 62 and the manifold supply pipe 71, as shown in Fig. 6. The horizontal face of the baffle plate on each side of the bracket 63 is inclined upwardly along its edge behind the depending portion 45 of the top frame 43, as 55 shown at 86 in Fig. 4. A rear baffle plate 87 is spaced apart from the baffle plate 83 and mounted therefrom by means of a plurality of brackets 88 suitably secured at one end to the plate 83, and at the other end to the plate 87. The plate 87 is reverse-lapped along its topmost edge, as shown at 89, to facilitate making and to strengthen the connection between the brackets and the plate, and has a plurality of slots 91 adapted to register with and to slide around the mixing chambers 54. The baffle plate 87 extends from the oven side 24 longitudinally of the burner portion 16, and is slotted at its end for a purpose to be explained presently. By spacing the baffle plates 83 and 87 apart, an air space is provided therebetween which serves as insulation between the plates which protect the valves and the manifold from the heat of the burners.

A metal channel 92 is arranged around the 75

manifold supply pipe 71, as shown in Figs. 2 and 6, and is suspended from the top frame 43 by securing the top face of the channel between the lug 49 of the top frame and the bifurcated 5 lug supporting the manifold supply pipe, as shown in Figs. 2 and 6. The channel 92 serves as a baffle against the heat from the burners 51 and 52 to protect the manifold supply pipe therefrom so that the heat from the burners cannot 10 be conducted along the pipe 71 to the manifold and thence to the valves to cause sticking of the valves. The channel, therefore, extends from the rear of the burner portion through the slotted end of the plate 87 to a line just behind the manifold 15 fold 62, where its end nearly abuts the front baffle plate 83.

In order to conceal the manifold and valves, a removable plate 93, shown particularly in Fig. 7, is provided to seat on the frame supporting 20 member 33 between the corner frame members 17 and 23. The plate 93 is cast with slots 94 extending up from its lower edge which register with the valve stems 77. Suitable words are cast on the face of the plate 93 around the slots 25 94 to indicate the valve positions by the relative positions of the handles 78 and the words around the slots 94.

A flange 95 is cast on the bottom edge of the plate 93 so that the flange follows along the 30 horizontal edge on each side of the plate around the slots 94, the flange being engageable behind the valve handles when the plate is in its normal position. Near the ends of the plate 93, a vertical flange 95' (Fig. 6) projects inwardly from the 35 inner face of the plate and is engageable with the edges of the ledges 27 provided in the corner frame members 17 and 23, the ends of the plate laps the ledges 27, as shown in Fig. 6, to provide against movement of the plate inwardly or 40 longitudinally of the burner portion.

Intermediate the ends of the plate 93 a plurality of depending flanges 96 are cast on the inner edge of the flange 95 and are arranged to engageably interlock behind the edge 38 intermediate the ends of the frame supporting member 33. The ends of the plate 93 are arranged 45 to rest against the ledges 27 of the corner frame members 17 and 23. The plate 93 is of such dimension that its top edge is concealed by the depending side 44 of the top frame but does not extend upwardly to the lower face of the top frame.

To clean or to adjust the valves or to adjust the air shutters 81, the plate 93 is removed by 55 prying between the plate 93 and the frame supporting member 33 until the fingers can be inserted therebetween at suitable finger lugs 97 projecting inwardly of the burner portion near the ends of the flange 95. The plate 93 is then 60 raised and the top tilted back towards the baffle plate 83, as shown by the dotted lines in Fig. 4. When the plate 93 has been raised until the flange 95 around the slots 94 clears the valve handles 78, and when the depending flanges 96 of the 65 plate clear the edge 38 of the frame supporting member 33, the plate may be removed by pulling outwardly on the bottom. In this manner, the valves are exposed and may be adjusted or cleaned, and the set screws 82 may be adjusted 70 to control the amount of air supplied to the mixing chambers 54.

The plate 93 may then be replaced by tilting and inserting its topmost edge under the depending side 44 of the top frame and by raising 75 the plate 93 until this edge rests in the angle

formed by the lugs 67 and the top frame. In this position, the slots 94 are aligned with the valve handles 78 and clear the handles, so that the bottom of the plate may be pushed back beyond the handles and the plate lowered to the position illustrated in Figs. 1 and 5.

It will be seen that the manifold 62 and the valves are positioned between the front baffle plate 83 and the removable plate 93, so that the manifold and valves are concealed from view 10 and are protected from the heat of the burners to provide against the valves sticking due to the heat. The manifold supply pipe 71 also is concealed from view and protected from the heat of the burners, in order that heat will not be conducted from the supply pipe 71 to the manifold 15 62 and to the valves, causing the valves to stick in operation.

It is thought that the invention and many of its attendant advantages will be understood from 20 the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A burner portion of a gas stove, comprising in combination a burner top, a manifold beneath 30 said burner top, burner valves communicating with said manifold, and a pair of spaced baffles arranged inwardly of said manifold and said valves and permitting circulation of air therebetween.

2. A burner portion of a gas stove, comprising the combination of a top frame, a plurality of burners, a manifold, a plurality of valves arranged to communicate with the burners and the manifold, and a pair of baffle plates arranged inwardly of said manifold and said valves, said baffle plates comprising a front baffle plate suspended from said top frame and a rear baffle plate supported from said front baffle plate, said baffle plates being spaced apart to permit circulation of 45 air therebetween.

3. A burner portion of a gas stove, comprising the combination of a top frame, a plurality of burners, a manifold, a plurality of valves arranged to communicate with the burners and the manifold, and a pair of baffle plates positioned between said burners and said valves to protect the manifold and the valves from the heat of the burners, said baffle plates comprising a front baffle plate having a plurality of slots arranged 50 to register with and fit around portions of the valves and a rear baffle plate spaced apart from said front baffle plate to permit circulation of air therebetween.

4. A burner portion of a gas stove, comprising the combination of a top frame, a plurality of burners, a manifold, a manifold supply pipe, a pipe connection for said manifold and manifold supply pipe, a plurality of valves arranged to communicate with the burners and the manifold, a pair of spaced apart baffle plates arranged inwardly of said manifold and said valves, the front baffle plate having a slot at its end arranged to register with and to fit around said pipe connection, and a rear baffle plate being spaced apart 65 from said front baffle plate to permit circulation of air therebetween.

5. A burner portion of a gas stove, comprising the combination of a top frame, a plurality of 70

- burners, a manifold, a manifold supply pipe, a pipe connection for said manifold and said manifold supply pipe, a plurality of valves arranged to communicate with the burner and the manifold, and a pair of baffle plates arranged inwardly of said manifold and said valves, said baffle plates comprising a front baffle plate having a plurality of slots arranged to register with and fit around portions of the valves and said pipe connection and a rear baffle plate spaced apart from said front baffle plate to permit circulation of air therebetween. 5
6. A burner portion of a gas stove, comprising the combination of a top frame, a plurality of 10 burners having mixing chambers communicating with said burners, a manifold, a manifold supply pipe, a plurality of valves arranged to communicate with the manifold and the mixing chambers, and a pair of baffle plates arranged 15 inwardly of said manifold and said valves, said baffle plates comprising a front baffle plate having a plurality of slots arranged to register with and fit around portions of the valves and a rear baffle plate spaced apart from said front baffle 20 plate to permit circulation of air therebetween, and having a plurality of slots arranged to register with and fit around said chambers to protect the valves and the manifold from the heat 25 of the burners. 25
7. A burner portion of a gas stove, comprising the combination of a top frame, a plurality of 30 burners, a manifold, a plurality of valves arranged to communicate with the burners and the manifold, and a pair of baffle plates positioned 35 between said burners and said valves to protect the valves and the manifold from the heat of the burners, said baffle plates comprising a front baffle plate and a rear baffle plate having one end thereof slotted. 40
8. A burner portion of a gas stove, comprising the combination of a top frame, a plurality of 45 burners, a manifold, a manifold supply pipe, a plurality of valves arranged to communicate with the burners and the manifold, and a channel member suspended from said top frame and arranged around said manifold supply pipe to protect the said supply pipe from the heat of the burner. 5
9. A burner portion of a gas stove, comprising the combination of a top frame, a plurality of 10 burners, a manifold, a manifold supply pipe, a plurality of valves arranged to communicate with the burners and the manifold, a channel member suspended from said top frame and arranged around said manifold supply pipe, and a pair 15 of spaced baffles arranged inwardly of said manifold and said valves and permitting circulation of air therebetween. 20
10. A burner portion of a gas stove, comprising the combination of a top frame, a plurality of 25 burners, a manifold, a manifold supply pipe, a plurality of valves arranged to communicate with the manifold and the burners, a channel member suspended from said top frame and arranged around said manifold supply pipe, and a pair 30 of spaced baffles arranged inwardly of said manifold and said valves and permitting circulation of air therebetween, said channel member and said pair of spaced baffles being interlocked and arranged to co-operate in protecting the 35 manifold, the manifold supply pipe and the valves from the heat of the burners. 40
11. A burner portion of a gas stove, comprising the combination of a frame supporting member, a plurality of burners, a manifold adapted to supply gas to said burners, a plurality of valves arranged to communicate with said manifold and said burners, said valves having handles positioned outside of the burner portion, and a removable plate arranged to seat on said frame 45 supporting member and in front of said manifold, said plate having a plurality of downwardly opening valve slots adapted to receive said valve handles, a horizontal flange on the bottom edge of said plate, vertical flanges adjacent the ends of said plate, the plate projecting laterally beyond said last mentioned flanges and the projecting portions being adapted to seal the opening of the frame structure. 45

CLAUDE M. DIBBLE.
